GEORGE M. PETTENGILL, OF HAVERHILL, MASSACHUSETTS, ASSIGNOR TO HAMEL SHOE MACHINERY COMPANY, A CORPORATION OF MASSACHUSETTS.

METHOD OF CHANNELING SHOE-SOLES.

1,399,024.

Specification of Letters Patent.

Patented Dec. 6, 1921.

Application filed April 9, 1919. Serial No. 288,666.

To all whom it may concern:

Be it known that I, GEORGE M. PETTENGILL, a citizen of the United States, residing at Haverhill, in the county of Essex and State 5 of Massachusetts, have invented certain new and useful Improvements in Methods of Channeling Shoe-Soles, of which the following is a specification, reference being had therein to the accompanying drawings.

10 In channeling a shoe sole outwardly as is done in the preparation of soles for turn shoes and insoles for welt shoes, much difficulty has been experienced in properly performing the operation at the point of a sharp toe. It has often been necessary to complete the operation by hand after running through a machine, in order to prepare the channel at the apex for the sewing operation. 15 Specially designed tools for use with the machines have been devised in attempts to overcome this difficulty, but these have not been entirely successful, especially on the more extreme shapes.

The present invention provides a method 20 by which the more pointed toes may be channeled successfully without requiring the use of special tools and at a single operation.

For a more complete understanding of the invention reference may be had to the accompanying drawings in which,—

Figure 1 is a diagrammatic plan view of a shoe sole partly channeled, with the tool at the point of the toe in position to channel one side of the sole after having channeled the 35 other side, as ordinarily done;

Figs. 2, 3, 4, 5 and 6 are diagrammatic views illustrating the relative positions of sole and tool at various stages of the operation, according to this invention; and

40 Fig. 7 is a diagrammatic view illustrating the application of the invention to a power machine having a one-direction linear feed.

A represents the sole, and B the channeling tool. In Fig. 1 the sole is represented as 45 having been channeled along the edge 1, tool B being at the apex of the toe in position to channel the side 2. The tool is ordinarily presented substantially normal to the line of the channel and in this position it is evidently necessary at the apex of the toe to turn the tool sharply relative to the work, in order to go about the angle of the channel. On very sharp toes, however, there is no room 50 for the shank of the tool to turn when the 55 blade is projecting into the channel at the

point of the toe, any such turning of the tool resulting in a lifting and tearing of the channel lip already formed, as illustrated at 3. This, of course, spoils the continuity of the channel at the apex and makes it difficult to 60 guide the channel guide of the sewing machine therein.

In order to overcome this difficulty this invention provides for turning the tool at either side of the apex of the channel angle 65 so that substantially no turning relative to the median line of the sole is required at the apex, this turning being accomplished where there is plenty of room therefor without danger of marring the channel lip. When the 70 tool is in the position illustrated in Fig. 2 it extends substantially normal to the line of the channel at a as is usual. On approaching the apex it is progressively made to assume an inclination toward the apex as at b, 75 Fig. 3, and as it nears the apex it occupies a position such as shown at c, Fig. 4, wherein the cutting edge of the tool lies substantially parallel to a line bisecting the angle of the apex. Upon passing the apex, the tool has 80 imparted thereto a slight retracting movement, and during or following this movement the tool is progressively inclined away from the apex, as seen at d, Fig. 5, the retraction of the tool from the apex providing 85 room for the turning of the tool without interference with the finished lip. This inclination proceeds until the tool has been brought into substantially normal position, as seen at e, Fig. 6, after which the operation 90 is completed in the usual manner. By this method, it is clear that substantially no turning of the tool takes place at the apex, such turning being accomplished as the tool approaches and recedes from the apex, thus 95 avoiding damage to the finished lip such as is occasioned by the common practice of turning the tool within the channel at the apex.

In applying this method to a power machine in which the sole is fed against the tool, the feed always being in the same linear direction, when the apex is reached and the sole must be reversed to work along the other side thereof, the tool must be moved with it. 100 This is represented in Fig. 7, in which the straight arrow shows the constant direction of feed. The tool is first shown in position a substantially normal to the edge 1. As the apex is approached the tool is inclined there- 105 110

toward as previously described, and when the apex is reached it is in the position *c*, in the same manner as disclosed in Fig. 4. At this point the sole must be turned about the apex

- 5 through the arc *m* in order to channel side 2 thereof. As no relative turning motion of the tool and the sole is permitted at this time according to this method of operation, the tool also must be swung through a like angle 10 *m'* with the sole. This resulting position of the tool is shown at *c'*, Fig. 7. The sole then continues to feed relative to the tool, and as the tool is retracted from the apex of the sole it is gradually turned in a position substantially 15 normal to the edge 2, its final position being shown at the point *e'* where it is in the same position as it was at the point *a*, in both cases extending substantially normal to the line of feed.

- 20 While this method has been described with reference to channeling of soles, it is evident that it might find equal applicability to other tools which operate within the channel,—for example, Gemming tools and the like, and 25 this invention is regarded as sufficiently broad to include all such operations.

Having thus described the invention, what is claimed is,—

- 30 1. The method of operating a tool in a channel about an angle which consists in imparting to the tool a partial turning movement in such manner as to change the angle of presentation of its cutting edge to the work while operating upon one side of said

- 35 angle, maintaining said angle of presentation substantially constant while passing the apex of such angle, and completing such turning movement while operating upon the opposite side of said angle.

- 40 2. The method of operating a tool in a channel about an angle which consists in relatively feeding the work against the tool edge while maintaining the angle of said edge to the median line of the work substantially 45 constant in passing the channel angle.

- 50 3. The method of operating a tool in a channel about an angle which consists in relatively feeding the work to the tool edge and turning the edge with the work when feeding about the apex of said angle.

- 55 4. The method of operating a tool in a channel about an angle which consists in relatively feeding the work to a tool edge and so turning said edge relatively to the work at one side of the apex of said angle as to permit said edge and the median line of the

work to be maintained at a substantially constant relative angle when passing the apex of said channel angle.

5. The method of operating a tool about an angle within a channel, the channel flap extending inwardly of said angle, which consists in turning said tool relative to the work at one side of the apex of said angle and maintaining its angular relation to the work substantially constant in passing the apex of said angle.

6. The method of operating a tool in a channel about the inner side of an angle which consists in relatively feeding the work 70 to the tool and inclining said tool toward the apex of said angle as it approaches said apex and away from said apex as it leaves said apex whereby substantial turning of the tool relatively to the work at the apex may be 75 avoided.

7. The method of operating a tool in a channel about an angle where the tool must be turned relative to the work, because of said angle, to be properly presented within 80 the channel, which consists in effecting at least a portion of said turning at one side of the apex of said angle.

8. The method of channeling a shoe sole outwardly about a pointed toe which consists in relatively feeding the tool against the work toward the point on one side, progressively inclining said tool toward said point as it approaches said point, channeling at the point with the tool pointing theretoward, 90 withdrawing said tool from the point and progressively inclining said tool in the reverse direction to channel the opposite side of said sole as it is withdrawn.

9. The method of channeling a shoe sole 95 outwardly about a pointed toe which consists in feeding the work substantially normally against the tool to channel toward the toe along one edge of the sole, turning the tool relative to the work to incline it toward 100 the point of the toe as it approaches said toe so that at the apex it points substantially directly theretoward, turning said sole together with said tool so that the sole is fed in a direction to channel along the opposite 105 edge of said sole, and progressively turning said tool into substantially normal position relative to said feed as it recedes from the apex of said toe.

In testimony whereof, I have signed my 110 name to this specification.

GEORGE M. PETTENGILL.
